UNITED STATES PATENT OFFICE.

EDWARD A. SCHOOLEY, OF DORMONT, PENNSYLVANIA.

RAILWAY SIGNAL TORPEDO.

Application filed August 6, 1924. Serial No. 730,444.

To all whom it may concern:

Be it known that I, EDWARD A. SCHOOLEY, a citizen of the United States, and resident of Dormont, in the county of Allegheny and 5 State of Pennsylvania, have invented certain new and useful Improvements in Railway Signal Torpedoes, of which the following is a specification.

This invention relates to railway torpedoes used on railways as audible signals and more particularly to torpedoes embodying an explosive charge, an enveloping casing of fibrous material and a ductile metal strip for detachably securing the torpedoes 15 to the rails of a railway track.

The principle object of this invention is to provide a novel form of enveloping casing composed of fibrous material, such as heavy paper, said casing being so formed 20 that the torpedo may be readily and quickly assembled by unskilled workmen and thus reduce the cost of production.

Another object is to provide a novel manner of mounting the ductile metal retaining 25 strip in the torpedo.

A further object is to provide a torpedo having the novel construction, design, and combination of parts hereinafter described and illustrated in the accompanying drawings.

In the drawings—

Figure 1 is a plan of the main body portion of the torpedo casing.

Figure 1^a is a plan of the reinforcing and 35 closure member of the casing.

Figure 1^b is a plan of the clip carrying member of the casing.

Figure 2 is a transverse sectional elevation 40 through the completed torpedo.

Figure 3 is a side elevation of a torpedo showing its appearance on a rail.

Referring more particularly to the drawings, which illustrate my invention, the letter A designates the enclosing fiber casing of 45 the torpedo as a whole. The main body of the casing is formed from a flat piece of heavy paper or fiber board, cut substantially octagon shaped, so as to provide alternate long sides 2 and short sides 3, the long sides 50 then being bent back on the blank so as to define a rectangle and to form retaining flaps 4. The central or rectangular portion of the main body of the casing is depressed so as to provide a dome-shaped explosive 55 retaining space 5, and a preformed car-

tridge or tablet 6 of explosive compound is mounted in the space 5.

After the explosive 6 is positioned in the space 5, a closure 7 composed of a rectangular sheet of fiber is mounted under the 60 explosive and secured to the main casing member by a quantity of waterproof cement. A second sheet of fiber 8, similar in size and shape to the closure sheet 7, is mounted on the sheet 7 and secured in place by a quantity of waterproof cement.

The sheet 8 is provided with a pair of spaced slots 9 through which a retaining clip or strip of ductile metal 10 is threaded. The metal strip 10 has its ends projecting 70 through the slots 9 and its central portion 11 overlying the portion of the sheet between said slots. Of course it will be understood that the strip of metal 10 may be riveted or otherwise secured to the sheet 8 75 if desired.

The sheet 8 is preferably positioned on the closure sheet 7 so that the portion 11 of the metal strip 10 is between the sheets 7 and 8 and is thereby held against endwise 80 movement by the cement between the sheets.

After the sheet 8 has been secured in position, the retaining flaps 4 are bent over the sheet 8 and secured in position by a quantity of waterproof cement and the parts are 85 thus all bound firmly together, and the edges of the sheets 7 and 8 are protected.

During the course of manufacture, and preferably before the assembling of the casing is started, the word "Danger" or other 90 suitable warning 14 is printed on the top face of the casing. After the casing has been assembled it is then dipped in or otherwise covered with a transparent waterproof material which impregnates and forms a 95 coating 15 on the casing so as to form a thoroughly waterproof article.

The flat bottom of the torpedo casing is 100 preferably provided with a coating of sand or other abrasive material 16 to prevent the torpedo slipping along the rail to which it is attached in use.

Those skilled in the art will readily appreciate the advantages of the above described form of torpedo. It is simple in 105 construction, and can be assembled by cheap and unskilled labor, it is free of any metal fastenings or parts except the soft ductile retaining strap, it is strong and durable, and it is absolutely waterproof.

While I have shown and described only one specific embodiment of my invention, it will be expressly understood that I do not wish to be limited thereto since various modifications may be made without departing from the scope of my invention as defined in the appended claims.

I claim—

1. A fiber case railway torpedo comprising an enclosing case, the main body portion of which is formed from one piece of material and comprises a dome-shaped explosive receiving portion and narrow flap members bent back along the edges thereof so as to extend slightly under said explosive receiving portion, an explosion tablet in said dome-shaped receiving portion, a substantially rectangular cover sheet mounted under said explosive and secured to said main body portion, a second substantially rectangular sheet mounted on and secured to said first named sheet, a ductile metal retaining strip secured to said second named sheet, and said flaps being bent over and secured to said sheets by a waterproof cement.

2. A fiber case railway torpedo comprising an enclosing case, the main body portion of which is formed from one piece of material and comprises a dome-shaped explosive receiving portion and narrow flap members bent back along the edges thereof so as to extend slightly under said explosive receiving portion, an explosion tablet in said dome-shaped receiving portion, a substantially rectangular cover sheet mounted under said explosive and secured to said main body portion, a second substantially rectangular sheet mounted on and secured to said first named sheet, a ductile metal retaining strip secured to said second named sheet, said flaps being bent over and secured to said sheets by a waterproof cement, and said entire case being coated with a transparent waterproof coating after it is assembled so as to permit the reading of printed matter placed on the case prior to the coating thereof.

3. A fiber case railway torpedo comprising an enclosing case, the main body portion of which is formed from a substantially octagon shaped blank having its center depressed to form a dome-shaped explosive receiving space and having its edges bent back to form narrow flaps adapted to extend slightly over said explosive space, a substantially rectangular cover sheet mount-

ed over said explosive space and secured to said main body portion, a second substantially rectangular sheet mounted over and secured to said first named sheet and having a ductile metal retaining strip secured thereto, said flaps being bent over said sheets and secured thereto by a waterproof cement, and an explosive tablet mounted in said explosive space.

4. A fiber case railway torpedo comprising an enclosing case, the main body portion of which is formed from a substantially octagon shaped blank having its center depressed to form a dome-shaped explosive receiving space and having its edges bent back to form narrow flaps adapted to extend slightly over said explosive space, a substantially rectangular cover sheet mounted over said explosive space and secured to said main body portion, a second substantially rectangular sheet mounted over and secured to said first named sheet and having a ductile metal retaining strip secured thereto, said flaps being bent over said sheets and secured thereto by a waterproof cement, and the entire case being coated with a transparent waterproof coating after it is assembled so as to permit the reading of printed matter placed on the case prior to the coating thereof.

5. A fiber case railway torpedo comprising an enclosing case, the main body portion of which is formed from a substantially octagon shaped blank having its center depressed to form a dome-shaped explosive receiving space and having its edges bent back to form narrow flaps adapted to extend slightly over said explosive space, a substantially rectangular cover sheet mounted over said explosive space and secured to said main body portion, a second substantially rectangular sheet mounted over and secured to said first named sheet and having a ductile metal retaining strip secured thereto, said flaps being bent over said sheets and secured thereto by a waterproof cement, the entire case being coated with a transparent waterproof coating after it is assembled so as to permit the reading of printed matter placed on the case prior to the coating thereof, and at least one face of said casing being provided with a coating of abrasive material to prevent slipping of the torpedo on the rail to which it is attached.

In testimony whereof I have hereunto set my hand.

EDWARD A. SCHOOLEY.
